UNITED STATES PATENT OFFICE.

JOHN JOSEPH ALLINSON, OF BARTLESVILLE, OKLAHOMA, ASSIGNOR, BY MESNE ASSIGNMENTS, TO DOHERTY RESEARCH COMPANY, OF NEW YORK, N. Y., A CORPORATION OF DELAWARE.

PROCESS OF DISTILLING OIL.

Application filed July 17, 1919. Serial No. 311,558.

To all whom it may concern:

Be it known that I, JOHN JOSEPH ALLINSON, a citizen of the United States, residing at Bartlesville, in the county of Washington, State of Oklahoma, have invented certain new and useful Improvements in Processes of Distilling Oil; and I do hereby declare the following to be a full, clear, and exact description of the invention, such as will enable others skilled in the art to which it appertains to make and use the same.

This invention relates to oil distillation and more particularly to a process of distilling oil by which the lighter constituents of the oil may be effectively and efficiently separated therefrom.

In the commercial refining of petroleum oil, it is common practice to "top" or "strip" crude oil before the oil passes into the stills proper, in order to remove therefrom the more volatile constituents such as benzene. By topping the crude oil before it passes into a still, the distilling operation is greatly expedited and the capacity of the stills is increased. In the usual topping plant, the fresh crude oil is ordinarily heated under pressure in a still or retort and the heated oil is then passed into a larger chamber to allow the lighter constituents to vaporize. The vapors formed in the chamber are then conducted to a condenser and the oil remaining in the condenser is conducted to the stills for complete distillation. The quantity and character of vapors obtained by such topping processes depend upon the kind of oil being treated and the temperature and pressure of the oil entering the vaporization chamber. Therefore, such processes do not provide an accurate and complete removal of the light constituents of the oil so that a further removal of the lighter constituents must also be made in the stills.

The primary object of the present invention is to provide a process of distilling crude petroleum oil in which the removal of the lighter constituents of the oil may be efficiently carried out and accurately controlled.

Another object of the invention is to provide a process of distilling oil under a vacuum pressure which may be effectively used in a continuous oil distillation treatment.

With these and other objects in view, the

invention consists in the improved process of distilling oil hereinafter described and particularly defined in the claims.

The various features of the invention are illustrated in the accompanying drawings, in which,

Figure 1 is a diagrammatic view in front elevation illustrating an apparatus in which a process of distilling oil embodying the preferred form of the invention may be carried out;

Fig. 2 is a view in vertical section of the improved vacuum still; and

Fig. 3 is a view in side elevation of the vacuum still.

The improved process of distilling oil embodying the preferred form of the invention may be carried out in the apparatus shown in Fig. 1 as follows: Crude oil from storage is conducted through a pipe 10 to a pump 12 and forced through a heat interchanger 14. The oil is heated in the interchanger to a temperature of from 200° to 300° F. depending upon the temperature of the residuum oil flowing through the interchanger, and is then conducted through a pipe 16 to the upper portion of a vacuum still 18. The oil under a slight pressure from the pump 12 enters the still 18 through a distributor 20 and is broken up into a fine spray by the distributor. When the oil is released in the still 18 in the form of fine spray, it starts to vaporize and the vaporization of the oil is carried out in a series of stages, there being one stage for each of the compartments 22, 24, 26, 28, 30, 32 and 34 of the vacuum still. The vapors formed in the various compartments of the vacuum still are positively drawn out of the compartments under a vacuum suction. The vacuum suction is created by a vacuum pump 36 which acts through a pipe 38, vacuum trap 40, pipe 42 and conduit 44 to draw the vapors out of the compartments into vapor-collecting conduits 46, 48 and 50. The vapors drawn through the conduit 44, the pipe 42, trap 40 and pipe 38 are compressed in the vacuum pump 36 and then conducted through pipe 52 to a dephlegmator 54 and from the dephlegmator 54 through a pipe 56 to a second dephlegmator 58. The vapors leaving the dephlegmator 58 pass through a pipe 60 into a coil 62 mounted in a condenser box 64. The vapors condensed

in the box 64 are removed through a pipe 68 and pass to storage. The vapors condensed in the trap 40 and dephlegmator 56 and 58 are removed through a pipe 70 and 5 pass to storage.

The vacuum still 18 is operated to remove the lighter constituents of the oil such as crude benzene, and the portion of the oil which is not vaporized in the still falls to 10 the bottom of the still in drops. The oil collecting in the bottom of the still is drawn out through a pipe 72 by means of a pump 74 and forced through a pipe 76 into a fire still 78 which forms the first of a series of 15 fire stills 78, 80 and 82. The fire stills 78, 80 and 82 may be operated in the usual manner to remove the various fractional condensates from the petroleum oil. In the 20 operation of the fire stills, it may be advantageous to admit steam with the oil passing through the stills in order to assist in carrying on the fractional distillation. Although the stills 78, 80 and 82 have been described as fire stills, these may be any of the 25 proved forms of stills for carrying on distillation by the application of heat. The residuum oil left in the still 82, which is usually called fuel oil, is removed through a pipe 84 and passes through the heat inter- 30 changer 14 to the act as a heating medium for preheating the fresh crude oil entering through the pump 12. The volume and temperature of the residuum entering the heat interchanger through the pipe 84 is 35 carefully regulated so that the oil passing through the interchanger will have a sufficiently high temperature to permit the lighter constituents of fresh crude oil to be removed in the vacuum still 18. The fuel 40 oil which is cooled in the heat interchanger 14 passes out through a pipe 86 through a pump 88 and may be conducted to storage through a pipe 90.

The construction of the vacuum still 18 is 45 shown more particularly in Figs. 2 and 3. The still 18 consists of an elongated cylindrical tank which is built up in sections connected by gas and vapor tight joints. The compartments 22, 24, 26, 28, 30, 32 and 34 50 of the vacuum still are separated by means of fine mesh screens 92 which are supported upon angle iron frames 94 mounted within the still. With this construction, the oil is broken into a fine spray as it enters the top 55 of the vacuum still through the distributor 20, and the non-vaporized oil is collected on the screen 92 below the distributor. While the oil passes through the screen 92 to enter the compartment 24 from the compartment 22, it is broken up into fine drops and is thus 60 in a fine drop or spray in passing through the compartment 24. In this way, the oil is broken up into fine drops by the screens 92 in passing from one compartment to the 65 next lower succeeding compartment. The

screens 92 divide the oil into a very large number of fine particles which expose a very large surface of the oil and thus expedite the vaporization. To further assist in the vaporization, the oil vapors are withdrawn under vacuum from each compartment of the still and any of the lighter constituents in the oil which are not removed in the upper compartments may be removed into the lower compartments and drawn 70 into the vapor-collecting pipes 46 and 48. The vapor is collected from the compartment 22 through pipes 94 which are connected with the collecting pipe 50. The inner ends of the pipes 94 are provided with 75 perforated spherical members 96 which act to screen the vapors passing into the pipes 94 and prevent liquor from being drawn into the collecting pipe 50. The vapors are withdrawn from the compartments 24, 26, 28, 30, 32 and 34 through tubes 98 which are mounted at opposite sides of each of the compartments and connected with T's 100 mounted in the vapor-collecting pipes 46 and 48. Over the end of each of the outlet 80 pipes 98 are mounted baffles 102 which prevent the liquor passing through the compartments from being drawn directly into the pipes 98. Below each of the baffles 102 and across the inlet ends of the pipes 98 are 85 mounted screens 104 which act to filter the vapors passing into the collecting pipes 46 and 48 to thus prevent the liquid oil from flowing into the collecting pipes 46 and 48. To further assist in preventing heavy oil liquids from passing into the vapor-collecting 90 pipes 46 and 48, screens 106 (Fig. 2) are mounted in the joints by which the T's 100 are connected respectively with the tubes 98 and the vapor-collecting pipes 46 and 48. Any liquid oil which reaches the vapor-collecting 95 pipes 46 and 48 will be held back by the screens 106 and will flow downwardly by gravity through the vapor-collecting 100 pipes and be discharged into the vaporizing 105 compartment 34. As shown in Fig. 3, man-holes 108 are 110 mounted at the upper and lower ends of the vacuum still 18 to permit access to the interior of the still. 115 With the process and apparatus described above, it will be seen that the lighter constituents of petroleum oil may be effectively removed from the oil without the use of heat other than the heat in the residuum 120 leaving a series of heating stills. Although it is best to maintain a sufficient volume and quantity of residuum to raise the temperature of the oil flowing to the vacuum still above 200°, it is not essential that the oil entering the vacuum still shall be at such a high temperature because if the 125 temperature of the oil entering the vacuum still is low, the vacuum pressure within the still may be materially reduced to insure 130

that all of the lighter constituents will be removed from the oil. With this arrangement, further, it is not necessary that the temperature of the oil entering the vacuum still shall be uniform in order to efficiently remove the lighter constituents, but any combination of temperature and vacuum may be used in the vacuum still for effectively removing the lighter constituents.

10 Vaporization of the oil in zones within the vacuum still also permits an extremely large surface of the oil to be exposed to insure the complete removal of the lighter constituents, the oil passing through each of the zones being in the form of a fine spray or drops.

Heretofore, many attempts have been made to provide a continuous distillation of petroleum under a vacuum. However, a continuous process of distillation under a vacuum has not been carried out on account of difficulties and limitations of mechanical construction involved in the operation of a vacuum still. With the improved process described above, however, a vacuum separation of the lighter constituents may be effectively carried out in a continuous distilling operation.

Although the residuum withdrawn from the still 82 is used for preheating the fresh crude oil passing through the vacuum still, the fractional distillates coming from the stills 78, 80 or 82 may be used in the heat interchanger 14 for preheating the crude oil.

35 The preferred form of the invention having been thus described, what is claimed as new is:

1. In the distillation of crude petroleum the steps comprising heating petroleum oil, passing the heated oil through a series of

compartments maintained under a partial vacuum, finely dividing said oil at the points of its admission to said compartments, vaporizing the lighter portions of the oil enclosed in said compartments by the vacuum in said compartments, separately withdrawing vapors directly from each of said compartments out of contact with the oil in the said chamber and condensing the said vapors.

2. In the distillation of crude petroleum the steps comprising imparting a preliminary heat to crude oil of a temperature below 300° F., passing the heated oil into a chamber and finely dividing said oil a plurality of times within said chamber, vaporizing the lighter portions of the oil enclosed in the chamber solely by the sensible heat of the oil and the maintenance of a partial vacuum in the chamber, removing the vapors by suction as they are formed in the chamber, removing residual oil from the chamber and subjecting it to fractional distillation and imparting preliminary heat to the incoming crude oil by a heat interchange with hot residual oil from the fractional distillation.

3. In the distillation of crude petroleum the steps comprising heating petroleum oil to a temperature between 200° and 300° F., spraying the oil progressively into a series of compartments maintained at sub-atmospheric pressure, vaporizing a portion of the said oil in the said compartments by means of the sensible heat of the oil, withdrawing the vaporized oil as soon as it is formed, and condensing the said vapors.

In testimony whereof I affix my signature.

JOHN JOSEPH ALLINSON.
